CLAIM

I claim the ornamental design for a cup assembly, as shown and described.

DESCRIPTION

FIG. 1 is a front perspective view of a cup assembly, showing my new design;

FIG. 2 is a bottom perspective view thereof;

FIG. 3 is a top view thereof;

FIG. 4 is a bottom view thereof;

FIG. 5 is a left side elevation view thereof;

FIG. 6 is a right side elevation view thereof;

FIG. 7 is a front elevation view thereof; and,

FIG. 8 is a rear elevation view thereof.

The broken lines in the figures depict environmental subject matter only and form no part of the claimed design.

1 Claim, 3 Drawing Sheets(56)
